UNITED STATES PATENT OFFICE.

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 22, 1926. Serial No. 110,923.

My invention relates to railway traffic controlling apparatus, and particularly to apparatus of the type comprising train carried governing means controlled at least 5 in part by alternating currents which flow through the track rails.

One object of my invention is the provision, in apparatus of the type described, of means for supplying energy to the train 10 carried means in accordance with train controlling current in the trackway, but which will not supply energy to such means in accordance with alternating currents flowing in adjacent transmission lines or in adjacent 15 tracks etc.

I will describe two forms of railway traffic controlling apparatus embodying my invention, and will then point out the novel features thereof in claims.

20 In the accompanying drawings, Fig. 1 is a diagrammatic view illustrating one form of railway traffic controlling apparatus embodying my invention. Fig. 2 is a view showing a modified form of the apparatus 25 illustrated in Fig. 1 and also embodying my invention. Fig. 3 is a view showing, in front elevation, the receiver E forming a part of the railway traffic controlling apparatus shown in the preceding views and 30 also embodying my invention.

Similar reference characters refer to similar parts in each of the three views.

Referring first to Fig. 1, the reference characters 1 and 1^a designate the track rails 35 of a stretch of railway track over which traffic normally moves in the direction indicated by the arrow. These track rails are divided, by means of insulated joints 2, into a plurality of successive track sections 30 A—B, B—C, etc. Each track section is provided with a track relay designated by the reference character D with an exponent corresponding to the location and connected across the rails adjacent the entrance end of 45 the corresponding section. Each track relay D is responsive to the relative polarity of the current supplied thereto, and controls an associated line relay designated by the reference character K with a suitable distinguishing exponent. Referring, for example, to relay K^A, this relay is supplied with energy from secondary 7 of a line transformer Q^A when relay D^A is energized in either direction. The primary 8 of trans-

former Q^A is constantly supplied with alternating current from a suitable source of energy, such as an alternator M, over line wires 3 and 3^a. Each of the remaining relays K is supplied with energy from the secondary 7 of an adjacent transformer Q, over the contacts of the corresponding track relay in the same manner that relay K^A is controlled by relay D^A.

Each track section is also provided with a track transformer designated by the reference character T with an exponent corresponding to the location and comprising a secondary 4 connected across the rails adjacent the exit end of the corresponding section through the usual impedance 6. The primary 5 of each track transformer T is supplied with current of one relative polarity or the other over contacts 15 and 16 of the adjacent line relay K from the secondary 7 of the corresponding transformer Q. As will be plain from the drawing, the rails of each section are provided with track circuit current of one relative polarity, which I will term normal relative polarity, when the line relay K for the section next 70 in advance is energized. Referring for example to section A—B, when relay K^B is energized, track circuit current of normal relative polarity is supplied to the rails of section A—B. Under these conditions contact 75 42 of relay D^A is swung to the left. When relay K^B is de-energized, however, back contacts 15 and 16 are closed and track circuit current of the opposite relative polarity, which I shall term reverse relative polarity, is supplied to the rails of section 80 A—B. Under these conditions contact 42 of relay D^A is swung to the right. It will be observed that the track circuit current thus supplied to each section flows through the two rails in series so that this track circuit current flows in opposite directions in the two track rails at any instant.

Means are also provided for at times supplying each track section with loop current which flows through the two rails of the section in parallel. For this purpose each section is provided with an impedance 12, here shown as a reactor, connected across the rails adjacent the entrance end of the section, and a second impedance 13, here shown as a resistor, connected across the rails adjacent the exit end of the section. A sec-

ond resistor 14 is connected across the rails at an intermediate point in each section.

The immediate source of loop current for each section is a loop transformer designated 5 by the reference character L with an exponent corresponding to the location and located adjacent the exit end of the section. Current supplied by this transformer flows through the rails of the section in parallel 10 and returns to the transformer through an auxiliary conductor designated by the reference character X with an appropriate distinguishing exponent which is connected to the mid-point of impedance 12 and extends 15 throughout the section between the track rails 1 and 1^a. Referring particularly to section A—B, when relay K^B is energized loop current flows from secondary 11 of transformer L^B, through wire 19, front contact 20 18 of relay K^B, wire 20, impedance 13, rails 1 and 1^a of section A—B in parallel, impedance 12, auxiliary conductor X^A and wire 21 back to secondary 11 of transformer L^B. When this circuit is closed, loop current 25 is supplied to the rails of section A—B and to conductor X^A throughout the length of this section. When relay K^B is de-energized, the circuit just traced is opened, and current flows from secondary 10 of transformer L^B, through wire 22, back contact 17 30 of relay K^B, wire 23, impedance 14, rails 1 and 1^a of section A—B in parallel, impedance 12, and thence through auxiliary conductor X^A and wire 24 back to secondary 10 of transformer L^B. When this circuit 35 is closed, loop current is supplied to the rails of the section and to conductor X^A only between point A and the points of connection of impedance 14 and wire 24 with the rails 40 of the section and the conductor X^A, respectively. It follows that section A—B is supplied with loop current throughout the length of the section or throughout a portion only of the section according as the 45 line relay K^B is energized or de-energized respectively. It should be pointed out, however, that when the rails are being supplied with loop current the current which flows down the rails in parallel returns through 50 the auxiliary conductor X, and that the direction of the loop current in the conductor is opposite to the direction of the loop current in the rails at a point in the section at any instant.

55 As shown in the drawing the section to the right of point C is occupied by a train indicated diagrammatically at V. Relay D^C is therefore de-energized so that contact 42 assumes an intermediate position and relay K^C is de-energized. Section B—C is therefore supplied with track circuit current of reverse relative polarity, and loop current is supplied to the rails of the section between point B and the point of connection 60 of resistor 14, this loop current also flowing

through the conductor X^B between the impedance 12 and the point of connection of wire 24. Relay D^B is energized in the reverse direction and relay K^B is picked up. Section A—B is therefore supplied with 70 track circuit current of normal relative polarity and loop current is supplied to the rails of this section and to the conductor X^A throughout the length of the section. In similar manner relay K^A is energized so 75 that track circuit current of normal relative polarity is supplied to the rails of the section to the left of point A and loop current is supplied to the rails of this section and to the conductor associated therewith. 80

The section to the left of point A is occupied by a second train indicated at V^a and provided with train carried means suitable for co-operation with the trackway apparatus described hereinbefore. The train carried means comprises a track receiver F comprising two magnetizable cores 30 and 30^a carried by the train in advance of the forward axle 28 and located in inductive relation with the two track rails 1 and 1^a respectively. Core 30 is provided with a winding 31 and core 30^a is provided with a similar winding 31^a, the two windings being connected in series in such manner that the voltages induced in these windings by track circuit current flowing in opposite directions in the two track rails at an instant are additive. The windings 31 and 31^a are connected, through an amplifier 32, with one winding 33 of an induction motor relay P. 95

The train V^a is also provided with a loop receiver designated by the reference character E which may be located at a convenient place on the train, as between the locomotive and tender. This receiver is similar to the track receiver but comprises also a third magnetizable core 30^b located in inductive relation with the auxiliary conductor extending through the trackway and carrying a winding 31^b. This winding is connected in series with the associated windings 31 and 31^a in such manner that the voltages induced in these three windings 105 by loop current, which flows in one direction in the two track rails and in the other direction in the auxiliary conductor at an instant, are additive. The windings of receiver E are connected, through an amplifier 34, with the other winding 35 of relay P. 110

When the train V^a occupies a stretch of track which is being supplied with track circuit current of normal relative polarity and with loop current, the relative polarity of the currents supplied to windings 33 and 35 through the receivers F and E is such that contact 36 of relay P is swung to the left, and a lamp G is then supplied with current from a suitable source of energy, such as a battery 37. Lamp G therefore becomes 120 125 130

lighted to indicate proceed. When the relative polarity of either the loop current or the track circuit current supplied to the stretch of track occupied by the train is reversed, the relative polarity of the currents supplied to windings 33 and 35 is such that contact 36 is swung to the right, completing the circuit for lamp Y which then displays a caution indication. Should the supply of either track circuit current or loop current to the stretch of track occupied by a train become interrupted, relay P would become de-energized and contact 36 would occupy an intermediate position in which the circuit for a third lamp R would be closed, thereby lighting this lamp to give a stop indication.

I will now assume that the train V^a proceeds through the stretch of track shown in the drawing. When the train enters section A—B the track circuit current of normal relative polarity and the loop current supplied to this section energize relay P so that contact 36 remains in the left hand position wherein it energizes lamp G to give a proceed indication. When the train enters section B—C however, reversal of the relative polarity of the track circuit current supplied to the rails of this section causes contact 36 of relay P to swing to the right, thereby lighting lamp Y which displays a caution indication. After the train passes the point of connection of resistor 14 with the rails of section B—C and of wire 24 with the conductor X^B, the interruption of loop current causes winding 35 of relay P to become de-energized so that contact 36 occupies its intermediate position, completing the circuit for lamp R which displays a stop indication. Should the train enter the section to the right of point C the interruption of track circuit current due to the shunting effect of the wheels and axles of train V, would de-energize winding 33 of relay P so that the train would continue to receive a stop indication.

As best shown in Fig. 3 the fluxes due to loop current in the rails 1 and 1^a encircle the rails in the same direction, as indicated at 39 and 40, and pass through the cores 30 and 30^a, of the receiver E. The flux which surrounds the conductor X, as indicated at 41, traverses the core 30^b in the opposite direction; however, and as explained hereinbefore, the windings of the receiver are so connected in series that the voltages induced in these windings by the loop current in the trackway are additive. If, however, the receiver is in the path of a stray flux, such for example as that due to alternating current in a transmission line or a second track parallel to the rails 1 and 1^a, this flux would thread through the three cores 30, 30^a and 30^b in the same direction. The voltages induced in windings 31^a and 31 by this stray

flux would tend to oppose the voltage induced in winding 31^b by the stray flux. By suitably proportioning the parts, the apparatus is arranged so that the resulting voltage supplied to winding 35 of relay P as a result of the separate voltages induced in the winding of receiver E by this stray flux is reduced to a negligible amount. It is therefore impossible, with apparatus embodying my invention, for stray flux due to current flowing in an adjacent conductor to create in the windings of the loop receiver, voltages which might result in improper operation of the train carried apparatus.

Referring now to Fig. 2, the train carried apparatus is exactly the same as that illustrated in Fig. 1, but the trackway apparatus has been modified so that track circuit current of normal relative polarity is constantly supplied to the rails of each section by the track transformer T, the primary 5 of which is supplied with alternating current from line wires 3 and 3^a. The relative polarity of the current supplied to primary 9 of each loop transformer L is controlled by pole changing contacts 25 and 26 on the adjacent track relay D. Referring particularly to section A—B, when relay D^B is energized, current of normal relative polarity is supplied to primary 9 of transformer L^B, over contacts 25 and 26. At the same time loop current is supplied from secondary 11 of transformer L^B, over front contact 27 of track relay D^B to the rails of section A—B and to conductor X^A throughout the length of the section. When relay D^B is de-energized, however, current of reverse relative polarity is supplied to the primary 9 of transformer L^B and loop current is supplied from secondary 10 of this transformer over back contact 28 of relay D^B to the rails of section A—B, and to conductor X^A between point A and the points of connection of resistor 14 and wire 24 with the rails and the conductor, respectively. The control of loop current for each of the remaining sections is similar to the control of loop current for section A—B. The operation of the apparatus illustrated in Fig. 2 is similar to the operation of the apparatus shown in Fig. 1, it being noted that in Fig. 2, the caution indication is obtained by a reversal of the relative polarity of the loop current instead of a reversal of the track circuit current as in Fig. 1. The receiver E is immune to the effects of stray fluxes however, as explained in connection with Fig. 1.

Although I have herein shown and described only two forms of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of railway track having an auxiliary conductor, means for supplying the stretch with loop current which flows at a given instant in one direction in the rails of the stretch and in the other direction through the conductor, a train carried receiver comprising three windings one in inductive relation with each rail and one in inductive relation with said conductor, said windings being connected in series in such manner that the voltages induced therein by loop current flowing in the trackway are additive, and governing means responsive to the voltages induced in said windings. 10
2. In combination, a stretch of railway track having an auxiliary conductor, means for supplying the stretch with loop current which flows in one direction in the rails of the stretch and in the other direction through the conductor, a train carried receiver comprising two windings one located in inductive relation with each track rail and a third winding located in inductive relation with said conductor, said windings being connected in series in such manner that the voltages induced therein by loop current flowing in the trackway are additive but that the voltages induced in said two windings due to current flowing in a conductor outside the trackway opposes the voltages induced in said third winding by such current, and governing means responsive to the voltages induced in said windings. 20
3. In combination, a section of railway track having an auxiliary conductor, means for connecting said conductor with the rails at one point in the section, a source of energy having one terminal connected with the rails and the other terminal connected with said conductor at another point in the section, a train carried receiver comprising two windings inductively related to the two track rails respectively and a third winding inductively related to said conductor, said windings being connected in series in such manner that the voltages induced in said three windings by currents flowing in one direction in the track rails and in the other direction in the conductor are additive, and governing means responsive to the voltages induced in said windings. 30
4. In combination, a section of railway track having an auxiliary conductor, means for connecting said conductor with the rails at one point in the section, a source of energy, means for connecting said source between said conductor and the rails at a second point or a third point depending upon traffic conditions, a train carried receiver comprising two windings in inductive relation with the two track rails re- 40
5. In combination, a stretch of railway track having an auxiliary conductor, means for at times supplying alternating current to the conductor and at least one rail so that current flows in opposite directions through said conductor and rail at an instant, a train carried receiver comprising a winding inductively related with said conductor and a second winding inductively related with said rail, said windings being connected in series in such manner that the voltages induced therein by alternating currents flowing in one direction in said rail and in the other direction in said conductor are additive, and governing means responsive to the voltages induced in said windings. 50
6. In combination, a section of railway track having an auxiliary conductor, means for connecting said conductor with the rails at one point in the section, a source of energy having one terminal connected with the rails and the other terminal connected with said conductor at another point in the section, a second source of energy connected across the rails of the section, a train carried receiver comprising two windings in inductive relation with the track rails respectively and connected in series in such manner that the voltages induced in said windings by currents which flow in opposite directions in the two track rails at an instant are additive, a second train carried receiver comprising two windings in inductive relation with the two track rails respectively and a third winding in inductive relation with said conductor, said three windings being connected in series in such manner that the voltages induced therein by currents which flow in the same direction in said track rails and in the opposite direction in said conductor are additive, and governing means responsive to the voltages delivered by said receivers. 60
7. In combination, a stretch of track having an auxiliary conductor, a train carried receiver comprising two magnetizable cores one located over each rail and a third magnetizable core over said conductor, means for at times supplying the trackway with alternating loop current which flows in one direction in said rails and in the other direction in said conductor at an instant so that the fluxes in said cores pass in one direction in said two cores and in the other direction in the third core at an instant, 70

three windings one on each said core all connected in series in such manner that the voltages induced in such windings by the alternating fluxes in said cores are additive, 5 and governing means responsive to the voltage delivered by said receiver.

8. In combination, a stretch of railway track having an auxiliary conductor, means for supplying the stretch with loop current which flows at a given instant in one direction in the rails of the stretch and in 10 the other direction through the conductor, means for supplying the rails of the stretch with track circuit current which flows 15 through the two rails in opposite directions, a train carried receiver comprising three windings one in inductive relation with each

rail and one in inductive relation with said conductor, said windings being connected in series in such manner that the voltages induced therein by loop current flowing in the trackway are additive, a second receiver comprising two windings in inductive relation with the two track rails and connected in series in such manner that the voltages induced therein by alternating current flowing in opposite directions in the track rails are additive, and governing means responsive to the voltages delivered by said receivers. 20 25 30

In testimony whereof I affix my signature.

HOWARD A. THOMPSON.
